UNITED STATES PATENT OFFICE.

RICHARD D. YOUNG, OF NEW YORK, N. Y.

DESIGN FOR A BOTTLE-HANDLE.

SPECIFICATION forming part of Design No. 20,355, dated December 2, 1890.

Application filed April 28, 1890. Serial No. 349,686. Term of patent 14 years.

To all whom it may concern:

Be it known that I, RICHARD D. YOUNG, of the city, county, and State of New York, a citizen of the United States, have invented a certain new and original Design for Bottle-Handles, of which the following is a specification.

This invention relates to a design for a handle for a perfumery-bottle.

10 The drawing represents a perspective view of this improved bottle-handle, the bottle being indicated in dotted lines.

15 The handle embodying this design consists of an upper ring 1, a lower ring 2, and ear-shaped handles 3, connected at their upper ends to the upper ring and at their lower ends to the lower ring, preferably at diametrically-opposite points.

In the use of a handle of this design the

upper ring surrounds the neck of the bottle 20 near the top thereof and the lower ring surrounds the bottle at the base of the neck, as illustrated in the drawing.

I claim as my invention—

25 The design for a bottle-handle, as herein shown and described, the same consisting of an upper ring, a lower ring, and ear-shaped handles connected at their upper ends to the upper ring and at their lower ends to the lower ring.

30 In testimony that I claim the foregoing as my invention I have signed my name in presence of two subscribing witnesses.

RICHARD D. YOUNG.
